RUSSELL H. WILHELM, OF EASTON, PENNSYLVANIA, ASSIGNOR TO INGERSOLL-RAND COMPANY, OF JERSEY CITY, NEW JERSEY, A CORPORATION OF NEW JERSEY.

STEEL RETAINER.

Application filed February 18, 1924. Serial No. 693,641.

To all whom it may concern:

Be it known that I, RUSSELL H. WILHELM, a citizen of the United States, and a resident of Easton, county of Northampton, and 5 State of Pennsylvania, have invented a certain Steel Retainer, of which the following is a specification, accompanied by drawings. This invention relates to drill steel retainers for rock drills, but more particularly 10 to that type of retainer in which a yoke embraces the drill steel and is suitably held or clamped in position upon the front head of the machine.

This invention is in a certain respect an 15 improvement upon the steel retainer described and claimed in my, co-pending application, Serial No. 683,142; filed, December 28, 1923. Retainers for the collared working implement of fluid actuated machines must be sturdy and rugged to withstand 20 the vibration set up in the operation of the machine and the rough usage to which they are subjected, whether the working implement be a drill steel, a coal pick, a tie 25 tamper steel, a pavement breaker steel or any other similar implement. In the event of breakage, these implement retainers must be so constructed that broken parts may be readily and conveniently replaced in order 30 that the time and labor required for repairs are reduced to a minimum. It is also desirable to hold the retainer in operative position to prevent the vibration of the machine from moving the retainer away from the working 35 implement, as well as to enable the retainer to be held in inoperative position when it is desired to remove the working implement from the machine.

The object of this invention is to produce 40 a retainer for the collared working implement of a fluid actuated percussive machine which is simple in its construction, is composed of but few parts, is comparatively inexpensive to manufacture and is sturdy and rugged to withstand the hardest kind of usage.

Another object of the invention is to improve in certain respects upon the retainer as shown in my copending application above referred to.

Further objects of the invention will hereinafter appear and the invention is shown

in one of its preferred forms in the accompanying drawings in which

Figure 1 is a top plan view of the front 55 end portion of a rock drill of the hammer type with a retainer for the working implement connected thereto,

Figure 2 is a similar view with the machine turned at right angles to Figure 1, and 60

Figure 3 is a view similar to Figure 2 but with one of the parts shown in vertical section and showing the retainer swung to an inoperative position.

Referring to the drawings the front end 65 portion of a hand held rock drill of the hammer type is shown for illustrative purposes having a cylinder A which is separated from the front head B by the front cylinder bushing C, and these parts are connected together by the usual spring pressed side bolts D. In this instance a working implement in the form of a drill steel E having a collar F is adapted to extend into the front head B for receiving the impact 70 75 blows of the fluid actuated hammer piston of the machine.

A pair of trunnions G is preferably formed on the front head B on opposite sides thereof and is in this instance located 80 in a plane offset from the central plane of the machine. Each trunnion is preferably formed with a flattened portion H, which faces toward the outer end of the machine. A pair of side arms J is in this instance 85 pivotally connected to the trunnions G and each trunnion is preferably formed with an opening K. A lug L on each side of the front head B serves as a stop for limiting the swinging movement of the side arms J 90 beyond the operative position of the retainer.

In order to limit the outward movement 95 of the collar F on the steel E relative to the front head B, a yoke O is adapted to embrace the steel in such a manner that under normal working conditions the steel is permitted to move freely within the yoke but cannot be entirely withdrawn from the front head B, because of the collar F. The yoke O is preferably formed with a raised portion P against which the collar F is adapted to abut and a pair of arms Q is connected to the yoke O on opposite sides thereof and ex-

tends substantially at right angles therefrom. The yoke arms Q are in this instance adapted to extend into the openings K of the side arms J, and a bearing cap R is 5 preferably screwed onto the end of each of the arms Q and is provided with a closed end portion R' which is adapted to bear against the flattened portions H of the trunnions G.

10 In order to cushion the outward movement of the yoke O, a coil spring S in this instance surrounds each of the yoke arms Q in each of the openings K. One end of each of the coil springs S is adapted to bear 15 against one end of the opening K and the other end preferably bears against the cap R. The bearing caps R are in this instance formed with holes U to enable a suitable tool 20 to be inserted therein for screwing or unscrewing the caps and thereby enable the tension of the springs S to be adjusted.

In the position of the retainer shown in Figures 1 and 2, the yoke O is held in operative retaining position about the drill 25 steel E to prevent the withdrawal of the steel E. The closed end portions R' of the bearing caps R are held against the flattened portions H of the trunnions G by means of the springs S and in this manner 30 the yoke O is securely held in retaining position, so that the ordinary jars and shocks set up in the operation of the machine will not move the yoke from this position. Whenever the end portion R' of the bearing caps R have been worn sufficiently 35 these caps may be readily replaced so that a comparatively inexpensive part may be substituted so that the life of the retainer may be considerably prolonged.

40 As shown in Figure 3, the yoke O may be swung away from the steel E to enable the steel to be withdrawn from the front head B and in this position the springs S will force the end portions R' of the bearing caps R against the trunnions G and thereby hold the retainer in inoperative position relative to the steel.

I claim:

50 1. A retainer for fluid actuated percussive machines comprising the combination with the front end portion of a machine of a collared working implement adapted to extend into said front end portion, trunnions on opposite sides of said front end portion having a flattened portion, said trunnions being in a plane offset from the central plane of the machine, side arms pivotally connected to said trunnions, a yoke adapted to embrace said implement, arms connected to said yoke at opposite sides thereof and extending at substantially right angles therefrom, a bearing member connected to one end of each of said arms, and spring means for cushioning the outward movement of said yoke and adapted

to force one end of said bearing member against the flattened portions of said trunnions to hold said yoke in operative retaining position.

2. A retainer for fluid actuated percussive machines comprising the combination with the front end portion of a machine of a collared working implement adapted to extend into said front end portion, trunnions on opposite sides of said front end portion having a flattened portion, said trunnions being in a plane offset from the central plane of the machine, side arms pivotally connected to said trunnions, a yoke adapted to embrace said implement, 70 arms connected to said yoke at opposite sides thereof and extending at substantially right angles therefrom into said side arms, a bearing member connected to one end of each of said arms, and spring means for cushioning the outward movement of said yoke and adapted to force said bearing members against the flattened portions of said trunnions to hold said yoke in retaining position, said bearing members being 75 adapted to adjust the tension of said spring means.

3. A retainer for fluid actuated percussive machines comprising the combination with the front end portion of a machine of a collared working implement adapted to extend into said front end portion, trunnions on opposite sides of said front end portion having a flattened portion, said trunnions being in a plane offset from the central plane of the machine, side arms pivotally connected to said trunnions, a yoke adapted to embrace said implement, arms connected to said yoke at opposite 90 ends thereof and extending at substantially right angles therefrom into said side arms, a renewable cap having a closed end portion connected to one end of each of said yoke arms, and a coil spring on each of said yoke arms for cushioning the outward movement of said yoke and adapted to force the closed end portions of said caps against the flattened portions of said trunnions to hold said yoke in retaining position, said cap being adapted to be adjusted to adjust the 95 tension of said springs.

4. A retainer for fluid actuated percussive machines comprising the combination with the front end portion of a machine of a collared working implement adapted to extend into said front end portion, trunnions on opposite sides of said front end portion having a flattened portion, said trunnions being in a plane offset from the central plane of the machine, side arms pivotally connected to said trunnions and formed with an opening, a yoke adapted to embrace said implement for limiting the outward movement of the collar on said implement, arms connected to said yoke at 100 105 110 115 120 125 130

opposite sides thereof and extending at substantially right angles therefrom into said openings in the side arms, a renewable bearing cap having a closed end portion screwed onto each of said yoke arms, and a spring on each of said yoke arms adapted to cushion the outward movement of said yoke and to force the closed end portion of said bear-

ing cap against the flattened portion on said trunnions to hold said yoke in operative 10 retaining position, said yoke being adapted to be swung away from said implement and held in inoperative position.

In testimony whereof I have signed this specification.

RUSSELL H. WILHELM.
